UNITED STATES PATENT OFFICE.

CLARE H. DRAPER AND JONAS NORTHRUP, OF HOPEDALE, MASSACHUSETTS,
ASSIGNORS TO HOPEDALE MANUFACTURING COMPANY, OF MILFORD,
MASSACHUSETTS, A CORPORATION OF MASSACHUSETTS.

FEELER-LOOM.

1,361,839.

Specification of Letters Patent. Patented Dec. 14, 1920.

Original application filed May 1, 1916, Serial No. 94,667. Divided and this application filed November 1, 1919. Serial No. 335,006.

To all whom it may concern:

Be it known that we, CLARE H. DRAPER and JONAS NORTHRUP, citizens of the United States, residing at Hopedale, in the county 5 of Worcester and Commonwealth of Massachusetts, have invented certain new and useful Improvements in Feeler-Looms; and we do hereby declare the following to be a full, clear, and exact description of the invention, such as will enable others skilled in the art to which it appertains to make and 10 use the same.

The present invention relates to an improvement in feeler looms and more particularly to an improvement in mechanism for preventing the occurrence of mispicks and double picks.

Weft replenishing looms employed in the production of high grade fabrics are commonly provided with filling feeler mechanism for the purpose of preventing the weft or filling in the active shuttle from becoming entirely exhausted, so as thereby to eliminate the weaving of short wefts or filling 20 threads into the cloth. Such looms are known as feeler looms. It sometimes happens that during the operation of even a feeler loom, short wefts occur thereby causing a blemish in the cloth. When only a 25 short weft or filling is laid in one shed, a condition obtains which is known in the art as a "mispick;" and when a short weft or filling is laid in the same shed with a 30 complete weft, a condition obtains which is known in the art as a "double pick." The 35 object of the present invention is to produce a loom in which the occurrence of mispicks or double picks is prevented.

One cause of the occurrence of double 40 picks during the operation of feeler looms is the fact that after the filling or weft replenishing operation, the filling end extending from the hopper to the selvage of the cloth (this filling end being known as the 45 incoming filling end) is liable to break and snap into the shed before it is caught and cut near the selvage by the temple thread cutter. The feature of the invention which prevents double picks from this cause 50 consists of a temple cutter which is located on the weft replenishing side of the loom and which operates positively—being controlled

in its operation by the movements of the lay—to cut the incoming filling end at the beginning of or during the second return beat 55 or backward movement of the lay after replenishment, that is, as soon as the first thread laid in the warp after replenishment is engaged and held by the warp on the first shedding operation succeeding re- 60 replenishment. This feature of the invention is not restricted to feeler looms, but may be employed in connection with any type of weft replenishing loom.

The features of the invention for preventing the occurrence of mispicks and double picks during the operation of a feeler loom are described in the following specification and particularly pointed out in the appended claims.

In the accompanying drawings illustrating the preferred form of the invention, Figure 1 is a plan of a portion of the weft replenishing side of the loom, showing the improved temple thread cutter, with the 70 filling detector located adjacent the feeler thread parting and clamping mechanism; Figs. 2, 3 and 4 illustrate the operation of the temple thread cutter, Fig. 2 showing the normal position of the parts, Fig. 3 showing the positions of the parts on the first beat-up of the lay after weft replenishment, Fig. 4 showing the positions of the parts on the second return or backward beat of the lay after weft replenishment; Fig. 5 is 75 a plan illustrating the various features of the invention.

The feeler loom to which the features of the present invention are applied may be of any usual or preferred form. The loom 90 illustrated in the drawings comprises a breast beam 5 on the right-hand end of which is secured a bracket 6 which supports the hopper and other parts of the weft replenishing mechanism "W." The lay 7 is 95 mounted for oscillatory movements toward and from the breast beam. Mounted on the breast beam is the usual temple indicated at 8. Fulcrumed in suitable journals secured to the front side of the loom and extending transversely thereof, is the change or rock shaft 9 connected at one end with the weft replenishing mechanism "W." When the filling feeler mechanism indicates 100

predetermined or critical exhaustion of filling on the bobbin in the active shuttle, the rock shaft 9 is adapted to be oscillated to set in operation the weft replenishing mechanism. The construction of the parts above enumerated and their mode of operation, together with other parts of the loom necessary to a disclosure of the present invention, are well-known to those skilled in the art.

The feature of the invention which prevents double picks by severing the incoming filling end before it can break and snap into the shed, consists of an improved temple thread cutter which is adapted to operate upon the incoming filling end on the second return or backward beat of the lay after the replenishing operation. This temple thread cutter comprises a longitudinally movable or reciprocatory cutting member 10 and an oscillatory member 11. The cutting edges of these members are so located that when they are in normal open position, any filling end extending from the fell of the cloth toward the replenishing end of the loom is in the path of their cutting movement. The member 10 is somewhat elongated in form, is mounted upon the temple 8 contiguous to the outer side thereof, and is retained in position by two pins 12 and 13 projecting laterally from the temple. These pins are received respectively in elongated slots 14 and 15 in the cutting member 10. The slot 15 is provided with a recess or shoulder 16 which is adapted to receive the pin 13 when the cutter is in normal position. The member 10 is retained in normal position by means of a spring 17 secured at one end to an eye 18 formed on the forward end of the member 10, and at the other end to a pin 19 fastened to the temple. It will be observed that the member 10 has a slight pivotal movement on the pin 12, and that the spring 17 is so situated with respect to the line connecting the pin 13 and the pin 12 that, whenever the member 10 is moved forward, and the recess 16 is thereby brought opposite the pin 13, the spring 17 will act to draw the forward end of the member 10 upwardly until the pin 13 is received in the recess 16.

The oscillatory cutting member 11 is pivotally mounted on a pin 21 projecting laterally from the rearward end of the reciprocatory cutting member 10. The oscillatory cutting member is provided with a cam slot 22 situated above the pivot 21. The rearward end of this slot registers with the slot 14 in the member 10, when the cutting members are in normal position, as shown in Fig. 2, and the forward end 23 of the slot 22 is formed somewhat at right angles with the rearward end. The pin 12 projects through the cam slot 22. When the cutting member 10 is moved rearwardly to-

ward the lay, the cutting member 11 is carried with it inoperatively until the forward side of the part 23 of the slot 22 comes into contact with the pin 12. The continued forward movement of the members 10 and 11 causes the forward side of the part 23 of the slot 22 to bear against the pin 12, thereby oscillating the member 11 on the pin 21 and closing it rapidly against the cutting edge of the member 10.

75

The improved temple thread cutter is adapted to be brought into operation upon an actuation of the rock shaft 9 by means of the filling feeler mechanism, and for this purpose it is so constructed that it depends for the preliminary movement which shifts it from normal to a secondary position upon the action both of the rock shaft and of the lay. The subsequent movements necessary to bring the thread cutting members into final position for the thread cutting operation are effected by means of a cam member 25 which is loosely pivoted at the hole or aperture 20 therein on a pin 26 projecting laterally from the reciprocatory cutting member 10. The rearward end of the cam member 25 projects downwardly as a bunter 27, and its forward end extends toward the front of the loom and is provided with a hook-shaped lug 28 which normally rests upon a shoulder 29 formed on a cutter arm 30 secured to the rock shaft 9.

When the filling feeler mechanism has indicated critical exhaustion of filling, and the rock shaft 9 is turned anti-clockwise, viewing Fig. 4, the arm 30 moves to the left and the shoulder 29 draws out from under the hook 28, and thereupon the cam member 25 swings on the pivot 26 under the tension of the spring 31 connected at one end to the arm 30 and at its other end to the member 25, until a cam surface 32 formed on the cam member comes into engagement with a stop pin 33 fast in the temple. The cam member 25 is then left substantially in the position shown in Fig. 3.

On the beat-up of the lay during weft replenishment, inasmuch as the arm 30 still remains in the position shown in the dotted lines in Fig. 3, the engagement by the lay with the bunter 27 is ineffective. On the first backward beat of the lay, however, after replenishment, the arm 30 swings to the right again, and the under part of the shoulder 29 engages the upper surface of the lug 28 at the end of the member 25, as shown in full lines in Fig. 3. On the next forward beat of the lay, which is the first filling feeling beat after replenishment, the lay comes into engagement with the bunter 27 and moves the member 25 forward, forcing the cam surface 32 against the stop pin 33 and the forward end of the member 25 under the shoulder 29. Thereupon, the upper side of the aperture 20 in the member 130

25 is forced against the pivot pin 26 and moves it downwardly, carrying with it the forward end of the reciprocatory cutting member 19, thereby turning the member 10 on the pin 12 until the recess 16 is clear of the pin 13. All the parts of the thread cutter are now in the position shown in full lines in Fig. 3. Upon the return or next backward beat of the lay, which is the second return beat after replenishment, the disengagement of the lay from the bunter 27 permits the spring 17 to draw the cutting member 10 rearwardly. The rearward movement of the member 10 carries the oscillatory member 11 with it until the part 23 of the cam slot 22 reaches the pin 12, whereupon the member 11 is caused to oscillate on the pin 21, thereby closing the cutting edge of the member 11 against the cutting edge of the member 10 and severing the filling ends extending from the selvage of the cloth outwardly toward the replenishing mechanism. The positions of the parts of the cutter at this time are shown in Fig. 4.

25 When the shuttle reaches the filling feeler side of the loom, and the lay beats forward on the next filling feeler beat, it strikes a projection 34 depending from the under side of the reciprocatory cutting member 10, and carries the member 10 toward the breast beam until the recess 16 is brought opposite the pin 13, whereupon the action of the lay upon the member 10 (cooperating with the spring 17) lifts the forward end of the member 10 until the pin 13 is received in the recess 16. At the time that the lay strikes the projection 34, it also strikes the bunter 27 of the cam member 25 and forces it forward, causing the forward end of the member 25 to ride up over the shoulder 29, until the hook 28 rests thereon in its normal position.

Although the thread cutter described above is intended primarily to sever the filling end left by the incoming bobbin, that is, the incoming filling end which extends from the selvage to the hopper, in order to prevent its breaking and snapping into the shed and thereby causing a double pick, this thread cutter also operates incidentally to sever the filling end left by the outgoing bobbin, that is, that part of the outgoing filling end which extends from the selvage to the usual feeler thread parting and clamping mechanism "P," which is located adjacent the weft replenishing mechanism and severs the outgoing filling end relatively near the shuttle.

It will be observed from the foregoing description of the mode of operation of the temple thread cutter that the liability of the incoming filling end being broken and snapped into the shed is practically eliminated. It is obvious that the incoming filling end must not be cut on the first pick of

the shuttle away from the weft replenishing side of the loom because there would then be nothing to hold the filling until it had been beaten up against the fell by the reed and been caught by the warp threads 70 on the next shedding. It is not desirable that the thread cutter should be permitted to operate upon this filling end while the lay is on its forward center. Accordingly, the thread cutter of the present invention is constructed to cut the incoming filling end during the second return beat of the lay after replenishment. 75

The present application is a division of our copending application, Serial No. 80 94,667, filed May 1, 1916.

Having thus described the invention what is claimed is:

1. A feeler loom having, in combination, a lay, a breast beam, a weft replenishing mechanism, a filling feeler mechanism, connections between the weft replenishing mechanism and the filling feeler mechanism including a rock shaft, and a thread cutter constructed and arranged for actuation by the lay and by the rock shaft so as to move from normal to secondary position on the indication of critical exhaustion of filling by the filling feeler mechanism, to remain in secondary position during the next forward beat of the lay, to be moved to a third position on the next forward beat of the lay, and to cut the outgoing and incoming filling ends extending from the selvage toward the weft replenishing mechanism on the next backward beat of the lay. 90

2. A feeler loom having, in combination, a lay, a breast beam, a weft replenishing mechanism, a filling feeler mechanism, connecting means between the two mechanisms, a temple, 105 a thread cutter comprising a reciprocatory cutting member mounted on the temple, an oscillatory cutting member mounted on the reciprocatory cutting member, and a cam member, and connections between the connecting means and the cam member, the parts of the thread cutter being constructed and arranged to perform their cutting operation on the third backward beat of the lay after the indication of critical exhaustion of 110 filling.

3. A weft replenishing loom having, in combination, a lay, weft replenishing mechanism, and a thread cutter located on the replenishing side of the loom having provision 115 by virtue of which its operation is deferred until the second backward beat of the lay after replenishment to sever the filling extending outwardly from the selvage. 120

4. A weft replenishing loom having, in combination, a lay, a breast beam, a weft replenishing mechanism, a rock shaft, a temple, and a thread cutter comprising a reciprocatory cutting member, an oscillatory cutting member, a cam member, and connections 130

between the rock shaft and the cam member, the reciprocatory cutting member being mounted on the temple and the oscillatory cutting member and the cam being mounted 5 on the reciprocatory cutting member, the cam member being adapted to be moved from normal position to a secondary position when the parts of the weft replenishing mechanism are positioned to cause weft replenishment 10 on an actuation of the rock shaft, and to be moved to a third position on the first forward beat of the lay after replenishment to bring the reciprocatory cutting member into position to coöperate with the oscillatory cutting member to cut the thread extending from the hopper to the selvage on the next 15 backward beat of the lay.

5. A feeler loom having, in combination, a filling feeler mechanism, a weft replenishing 20 mechanism, connections between the two mechanisms including a cutter arm, a breast beam, a lay, a temple and a temple thread cutter comprising a reciprocatory cutting member mounted on the temple, an oscillatory cutting member, a cam member, the two latter members being mounted on the reciprocatory cutting member, connections between the cutter arm and the cutter members, pin and slot connections between the reciprocatory and oscillatory cutting members, and means for moving the thread cutter members toward the lay during the thread cutting operation, the reciprocatory cutting member and the cam member having provision 25 whereby, on the next forward beat of the lay after the cutting operation, the cutter members are restored to normal position.

6. A weft replenishing loom having, in combination, a lay, a weft replenishing 30 mechanism, a rock shaft, and a thread cutter constructed and arranged to be actuated by the rock shaft and by the lay to be moved from normal to a secondary position on the beat of the lay resulting in an actuation of 35 the rock shaft, to remain in secondary position on the next beat of the lay, to be moved to a third position on the next beat of the lay, and to perform the thread cutting operation on the third backward beat of the 40 lay after the actuation of the rock shaft.

7. A weft replenishing loom having, in combination, a breast beam, a weft replenishing mechanism, a rock shaft, an arm fast thereon, a lay, and a thread cutter mounted 45 on the breast beam comprising a reciprocatory cutting member, an oscillatory cutting member, a cam member loosely connected

with the rock shaft arm adapted to move from normal to secondary position and to be disconnected from the arm on an actuation of the rock shaft and to move the reciprocatory cutting member from normal to a secondary position on its engagement with the lay on the forward beat of the latter after the weft replenishing operation, 60 and means for causing the reciprocatory and oscillatory cutting members to perform their cutting operation upon the disengagement of the lay from the cam member.

8. A weft replenishing loom having, in combination, a lay, weft replenishing mechanism, and a thread cutter comprising a reciprocatory blade, an oscillatory blade, and means for actuating the blades having provision by virtue of which their actuation is 70 deferred until the second backward beat of the lay after replenishment to sever the filling extending outwardly from the selvage.

9. A feeler loom having, in combination, a lay, a breast beam, a weft replenishing 75 mechanism, a filling feeler mechanism, said mechanisms being mounted on opposite sides of the loom, a thread cutter mounted on the weft replenishing side of the loom constructed and arranged to cut the outgoing 80 and incoming filling ends extending from the selvage toward the replenishing mechanism, on the second backward beat of the lay after weft replenishment, and a filling detector mounted on the breast beam and 85 situated between the thread cutter and the weft replenishing mechanism.

10. A feeler loom having, in combination, a lay, a breast beam, a weft replenishing 90 mechanism, a filling feeler mechanism, a thread cutter situated on the weft replenishing side of the loom and adapted to cut the outgoing and incoming filling ends near the selvage at one operation on the second backward beat of the lay after weft replenishment, and a filling detector mounted on the 95 side of the loom remote from the filling feeler mechanism.

11. A feeler loom having, in combination, a lay, a breast beam, a weft replenishing 100 mechanism, a filling feeler mechanism, and a thread cutter situated on the weft replenishing side of the loom and adapted to cut the outgoing and incoming filling ends near the selvage on the second backward beat of the 105 lay after weft replenishment.
